UNITED STATES PATENT OFFICE.

JOSEPH L. JACKSON, OF GLASTONBURY, CONNECTICUT.

STOP-MOTION.

1,046,793.

Specification of Letters Patent.

Patented Dec. 10, 1912.

Application filed September 27, 1910. Serial No. 584,011.

To all whom it may concern:

Be it known that I, JOSEPH L. JACKSON, a citizen of the United States, and a resident of Glastonbury, in the county of Hartford and State of Connecticut, have invented new and useful Improvements in Stop-Motions, of which the following is a specification.

My invention relates more particularly to warp stop motions of the electrical type, and 10 is illustrated in connection with a harness loom, although it is susceptible for use with looms of other kinds.

Referring to the drawings: Figure 1 is a front view of a portion of a loom in which 15 the invention is embodied. Fig. 2 is a detail perspective view of a part of the device constituting the invention. Fig. 3 is a top view of a portion of a heddle bar. Fig. 4 is a side view of the same showing the connection open. Fig. 5 is a transverse sectional view on the line 5, 5 of Fig. 4. Fig. 6 is a view similar to Fig. 4 showing the connection closed. Fig. 7 is a transverse sectional view on the line 7, 7 of Fig. 6. Fig. 20 25 8 is a view showing somewhat diagrammatically a knock-off mechanism forming part of the stop motion.

Referring to the drawings *a* denotes a part of the frame of a loom, *b* a harness, *c* 30 the upper heddle bar, *d* the lower heddle bar, and *e* are the heddles, which may be of any well-known form such as the ordinary wire heddles.

The invention consists in means which are 35 made operative when one of the warp threads breaks for moving a part of a knock-off device into the path of a moving part of the loom in order that the knock-off device may be operated to stop the loom.

40 In carrying out my invention I make use of an upper heddle bar of peculiar construction. It comprises two strips of conducting material 1, 2, extending throughout the length of the bar and embedded in and 45 separated from each other by insulating material 3, these strips being wholly protected by said insulating material except along their upper edges which are exposed.

Supported on insulating standards 10, 11, 50 at the side of the machine are bars 12, 13, of conducting material, and to one of these bars 12 one of the conducting strips 1 of the heddle bar is electrically connected as by the wire 14. To the other bar 13 there is 55 secured a spring 15 which at its other end

carries a contact finger 16 which is pivoted to the insulating material 3 of the heddle bar as indicated at 17 in Figs. 4 and 5. A clip 18 is formed at the end of the strip 2 adjacent to the contact finger 16 which is 60 adapted to enter said clip when the frame is in its low position as indicated in Fig. 6.

By reference to Fig. 1 it will be noted that when the harness is in its upper position the spring 15 will cause the contact finger 16 65 to be withdrawn from the clip 18, and thus break the circuit between the strip 2 and the bar 13. These bars 12, 13 are connected into a circuit including a source of electric energy such as a battery indicated at 19, 70 and which leads to a knock-off mechanism, one frame of which is conventionally shown in Fig. 8 in which 20 denotes the latch connected with a starting handle 21, and *m* is a magnet connected with said latch. 22 represents the lay and 23 a bumper carried by 75 the lay.

While the machine is running with all the warp threads intact, each warp thread holds its heddle up off of the upper heddle bar 80 when the harness is in its low position, which means that there is no electrical connection between the two strips of conducting material embedded in the upper heddle bar. If however one of the warp threads 85 breaks the heddle drops so that its upper loop rests on the upper heddle bar as indicated at *e* in Fig. 1, with the result that when the harness is in its low position with the contact points 16 engaging the clip 18, 90 the electric circuit is closed. This energizes the magnet *m* drawing down the latch 20 into the path of movement of the bumper 23 and the lay 22, and at the next movement of the lay this bumper is engaged and the starting handle 21 is thrown over to the opposite position from that shown in Fig. 8, and the loom is stopped. As soon as the warp thread is repaired the starting lever is thrown back to the position of Fig. 8 and 100 the loom is again thrown into operation and will continue until another warp thread breaks, allowing its heddle to close the circuit between the strips 1, 2, and when the harness reaches its low position the magnet 105 is again energized to bring the knock-off mechanism into operation.

It is of course apparent that by simple alteration the spring 15 can be connected with the strip 2 and the circuit can be made 110.

and broken at the bar 13. I am also aware that there are other alterations and modifications of which the invention is susceptible.

I claim:

- 5 1. In a device of the character described the combination with a loom frame, harness, heddle bars of insulating material, a pair of conducting strips embedded therein with their upper edges exposed, conductor bars arranged at the side of the machine on insulated supports and connected into an electric circuit, an electric connection from one strip to one bar, a spring member secured at one end to the other bar and at the other end 10 pivotally connected with the heddle bar, a contact clip on the other strip adapted to be engaged by the end of said spring at the low position of the harness, heddles having eyes through which said heddle bar passes 15 and adapted to electrically connect said strips when a warp thread breaks, and a knock-off device arranged in operative relation with the loom driving mechanism and having a part normally held out of operative 20 position, and a device included in said circuit and adapted to operate said part when the circuit is closed.
2. In a device of the character described a loom frame, a plurality of harness, a heddle bar of insulating material for each harness, a pair of conducting strips embedded in each of said heddle bars with their upper edges exposed, a pair of conductor bars arranged at the side of the machine on insulated supports and connected 30 into an electric circuit, electric connections from one of said bars to one conducting strip of each heddle bar, spring members secured at one end to the other bar and at their 35

opposite ends pivotally connected with each 40 heddle bar, contact clips on the other strip of each heddle bar adapted to be engaged by the ends of said springs when the harness is in its low position, a set of heddles for each harness having eyes through which the 45 heddle bars pass, and adapted to electrically connect the conducting strip of each heddle bar when a warp thread breaks, a knock-off device arranged in operative relation with the loom driving mechanism and having a 50 part normally held out of operative position, and a device included in said circuit and adapted to operate said part when the circuit is closed.

3. In a loom the combination with a frame, harness, upper and lower heddle bars, heddles and warp threads, loom driving mechanism and a knock-off device associated therewith and having a part normally held out of operative position, of a pair of electric 60 conductors arranged at the side of the machine and connected into an electric circuit, a pair of conducting strips embedded in one of said heddle bars and exposed along their 65 upper edges, an electrical connection between one of said conductors and one of said strips, a spring member connected at one end with the other bar and having its opposite end slotted, a headed pin on said heddle bar adapted to receive the slotted end of the 70 spring, a contact finger at the end of said spring and a clip on the other conducting strip adapted to be engaged by said finger when the harness is in its low position.

JOSEPH L. JACKSON.
